Primary Examiner — Selina Sikder(74) *Attorney, Agent, or Firm* — Dunlap Bennett & Ludwig PLLC(57) **CLAIM**

The ornamental design for a portion of wall-mounted control panel, as shown and described.

DESCRIPTION

FIG. 1 is an isometric view of a portion of wall-mounted control panel;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the drawings illustrate portions of the portion of wall-mounted control panel that form no part of the claimed design.
